UNITED STATES PATENT OFFICE

WILLIAM J. TREMPE, OF NORTH BILLERICA, MASSACHUSETTS

AUTOMATIC WIRE SCREEN GUIDE FOR PAPER MAKING MACHINES

Application filed July 14, 1930. Serial No. 467,792.

This invention relates generally to a means for automatically controlling and guiding the path or run of the wire mesh screens used in paper making machines of the Fourdrinier

5 type. More particularly, the invention relates to improved features of construction which render the automatic control means more practical by increasing the sensitivity of the control but yet permitting a more rugged construction of the parts. While it

10 is not new to provide a means for automatically guiding and controlling a traveling wire mesh screen in a paper making machine, such earlier types of machines have had various limitations and are open to various objections in use. In applying the automatic mechanism to machines for controlling the course or path of the wire mesh screens,

15 the application of the automatic control mechanism depends upon whether or not the automatic control device is to be applied to what is known in the trade as a right hand or a left hand machine. Heretofore in the prior art, it has necessitated two distinct automatic control mechanisms for use on a right hand and left hand machine respectively, so that they were not interchangeable.

20 One of the objects of the present invention is to provide an automatic device so constructed that by a slight change in assembly, the same part of the device may be used interchangeably for mounting on either a right hand or left hand machine.

25 A further object of the present invention is to provide an automatic control mechanism for the wire mesh screen which is susceptible to a wider range of adjustment under various conditions of use, and upon various types of machines.

30 In machines heretofore employed where what is known in the trade as a guiding pan has been employed to contact with the edge of the traveling wire mesh screen, the guiding element has been detachably fixed to an arm by rivets or other suitable means, so that in certain relative positions of the guiding pan and the wire mesh screen, the screen frequently is damaged by engagement with the projecting securing means. As the wire mesh screens on the paper machines are deli-

cate and are very expensive, the likelihood of damage and injury to the controlling pans heretofore used, constitute a serious defect and objection.

35 A further object of the present invention is to provide a controlling pan which will overcome the objections above referred to in the machines of the prior art and produce a controlling pan element which will minimize, if not eliminate, the possibility of injuring the delicate and expensive wire screen mesh belts, particularly under any unusual or abnormal conditions when there has been an abnormal movement of shifting in the course or path of the wire screen.

40 One preferred selected embodiment of the invention is shown in the accompanying drawings for purposes of illustration.

45 In the accompanying drawings:

50 Fig. 1 is a fragmentary end view showing one end of a guide roller over which the wire screen passes and also showing a roll positioning mechanism and the automatic wire screen guide mechanism in control position on a right hand machine.

55 Fig. 2 is a side view showing the automatic wire guide mechanism in controlling and guiding relation relative to the wire screen passing over the roll.

60 Fig. 3 is a top plan of the bracket which normally supports the operating mechanism of the automatic wire screen guide showing the position the bracket would occupy in a right hand machine.

65 Fig. 3a is an enlarged fragmentary view showing the post detachably mounted in the bracket.

70 Fig. 4 is a view of the same bracket illustrated in Fig. 3, but reversed to show the position the bracket would assume for application to a left hand machine. The position of the bracket illustrated in Fig. 1, in the left hand machine the wire would be traveling in a direction opposite to that of the full line arrow.

75 Fig. 5 is an end view of the roller and the roll positioning or shifting mechanism but differing from Fig. 1 in showing the relative position of the pawl yoke or saddle, and the ratchet wheel with the roller advanced

half a revolution from that indicated in Fig. 1.

Fig. 6 is a side view of the automatic wire screen guide mechanism similar to Fig. 2 but indicating a different position of the wire screen guide relative to the roller over which it passes and also making a corresponding change in the position of the controlling pawl and the mechanism actuated thereby.

Fig. 7 is a view taken on the line 7—7 of Fig. 6.

Fig. 8 is a fragmentary view of the roll positioning or shifting mechanism showing the engagement of a pawl on one side of the pawl yoke or saddle, engaging a ratchet tooth on one side of the ratchet wheel or gear which shifts one end of the guiding roller to correct or compensate for the shifting of the wire screen from a normal position.

Fig. 9 is a section of the guiding control pan integral with the arm.

Fig. 10 is a diagrammatic view showing the guiding roller with the wire screen passing thereover and indicating in an exaggerated form the manner in which one end of the guiding roller is shifted to correct or compensate for the shifting movement of the wire screen upon the roller from a normal course of travel.

The roll shifting or positioning mechanism illustrated in more or less diagrammatic form in Figs. 1, 5 and 8, in detail construction forms no part of the present invention, but is merely illustrated as one form of roll positioning or shifting mechanism, to which the automatic wire screen guide constituting the subject of the present invention may be applied. It is understood that the present invention may be used in combination with and applied to other types of roll shifting mechanism, which other types are well-known in the art.

The roll shifting or positioning mechanism illustrated in Figs. 1, 5 and 8 comprises a stationary frame 1 which is mounted on the paper making machine (not shown) in any suitable manner.

The guide roller 2 is supported on a slideable guide or block 3 through a suitable ratchet or standard 4 which supports a bearing block or standard 5 at one end of the roller 2, in a manner well-known in the art. The guide or sliding block 3 is movable on a guide or rail 6 formed integral with the frame 1. The relative shifting movement between the frame 1 and the roller 2, is effected through a pawl and ratchet mechanism. As shown, a ratchet wheel 7 is threaded upon a screw rod 8 affixed in the frame 1. Through a forked frame, (not shown) the shifting of the ratchet wheel in one direction or the other upon the screw rod will shift the slideable guide 3 in a corresponding direction, so that one end of the roller 2 will be likewise moved. The showing of this form, although it con-

stitutes no part of the present invention has been illustrated for purposes of diagrammatic representation. The opposite faces or sides of the ratchet wheel 7 are provided on one side with ratchet teeth 9 extending in one direction, and the other side or face of the ratchet wheel are provided with ratchet teeth 10 extending in the opposite direction to the teeth 9 so that by movement of the pawl saddle or yoke 11, either to the right or left, the pawls 12 or 13 will engage the ratchet teeth 9 or 10 respectively and effect rotation of the ratchet wheel 7 which will in turn result in movement of the ratchet wheel 7 either to the right or left which will effect a corresponding movement of the end bearing for the roller 2. The vertical reciprocation of the pawl saddle 11 is effected through an eccentric cam 14 rotatable with the roller 2 and the link 15. During the normal operation when the wire mesh screen 16 is guided over the roller 2 in its normal course or path, the pawl, yoke or saddle 11 is so controlled and guided by a link 17 controlled by the automatic wire screen guide mechanism constituting the subject of the present invention and hereinafter to be more fully described, that the pawls 12 and 13 in their vertical reciprocatory movement do not engage either of the ratchet teeth 9 and 10, as in the actual machine, there is sufficient clearance between the pawls and the ratchet teeth to permit this vertical reciprocatory movement. However, if the wire screen 16 for any reason should shift from its normal path the automatic screen guide mechanism actuates the pawl yoke 11 to effect what is known in the trade as a dogging movement which is effected by engagement of the pawl and the ratchet teeth of the wheel 7 in the proper direction to obtain a shifting or corrective movement of the roller 2 in order to compensate for the shifting of the travel of the wire screen guide 16 from its normal path.

While the roll positioning and shifting mechanism above described constitutes in detail no part of the present invention other than as an element in the general combination, the description in such detail as has been given, is thought to be helpful in showing the necessity for the positive and sensitive control by the automatic screen guide which determines and controls the performance of the roll positioning and shifting mechanism. In order that the required positiveness and sensitiveness of the control in the automatic screen guide may be obtained, the construction and arrangement of the parts of the mechanism constituting the automatic wire screen control means must be of substantial and rugged construction to stand up under the conditions of use for a period of time and to also permit adjustment to varying conditions and also adjustment for wearing of parts. In view of the very slight movement necessary to actuate the roll posi-

tioning mechanism, it is essential that the construction and arrangement of parts in the automatic screen guide be such that there is little if any lost motion.

- 5 The construction of the preferred selective embodiment of the automatic wire screen guide constituting the subject of the present invention, is perhaps best illustrated in Figs. 1, 2, 6 and 7. As there shown, a bracket indicated generally as 18 is provided. The bracket is provided with a base 19 adapted to be secured to the machine, and with an arm 20 offset from the base by a connecting portion 21.
- 10 The arm 20 is provided with a slot 22 to permit adjustment of parts in a manner hereinafter to be more fully set forth. A lug 23 is formed integral with the bracket, said lug being provided with an aperture adapted to receive the post 24 removably mounted thereon.

15 Fig. 3a is an enlarged fragmentary view showing more clearly the manner of immovably or detachably mounting the post in the bracket. As shown, one end of the post is threaded, the threaded end extending through the aperture in the lug 23. The post is retained in position by suitable locking means such as the nuts 25-26 arranged one on each side of the lug.

20 It is understood that other suitable and well-known equivalent means may be employed for detachably or removably mounting the post. One of the distinct advantages in providing for the removable mounting of the post, is that such a feature of construction makes possible the use of a single bracket upon either a right hand or left hand machine. All that is required in order to make the necessary change from a right hand machine or vice versa is to remove the operating mechanism for the automatic wire screen guide (hereinafter to be more fully described) from the bracket and to remove the post 24 from the bracket and to then reverse the bracket and reposition the post so that it projects from the opposite side of the bracket after which the automatic guide mechanism may be again assembled.

25 As shown, the automatic wire screen guide mechanism is mounted on a frame comprising the bracket illustrated in Fig. 3 designated generally as 27, and an adjustable arm 28 for pivotally supporting at one end a pan supporting link 29. The arm 28 is provided with a slot 30 which cooperates with the slot 22 to permit adjustment of the arms 20 and 28 in different relative positions to permit the pivotally supported and weighted pan arm 31 to be properly positioned relative to the traveling wire screen 16. The two arms 28 and 20 may be clamped in properly adjusted relation in any suitable manner such for example as by the headed bolt 32 which passes through the slots 22 and 30 and retained in

properly adjusted position by the wing nut 33.

30 The pan supporting link 29 is pivotally supported intermediate to its ends by a pin 34 carried in the end of the arm 28. The pan arm 31 is pivotally supported at the upper end of the link 29 so that the point of pivotal support of the pan arm is between, the guiding pan 35 which contacts with the traveling wire screen 16, (after it has passed over the roller 2), and the lower weighted end 36 of the pan arm so that the weighted portion of the arm will tend to keep the pan in operative and guiding relation relative to the traveling wire screen. By such an arrangement, if there is any sudden amplified shifting movement of the wire screen, the pan and the supporting arm will be shifted and actuated by the wire screen, but the wire screen will not be injured as would be the case if the pan 35 were positively fixed upon the link 29. The dotted line position of the pivotally supported and weighted pan arm 31 illustrates an amplified movement of such pan supporting arm due to a sudden shifting of the wire screen. The movements of the pan arm 31 is transmitted to the link 17 which controls the roll shifting or positioning mechanism, through the link 29, to the link 37 through a universal joint connection, and from said link 37 to said link 17 through a bell crank 38 which is pivotally supported on the post 24. A suitable universal joint connection is interposed between one end of the link 37 and one arm 39 of the bell crank, and a suitable universal joint connection is interposed between one end of the link 17 and the other arm 40 of the bell crank. The universal joint connection at the ends of the arms 39 and 40 of the bell crank, is shown as comprising a plurality of blocks 41-42, each block being provided with a stud 43-44 respectively. The stud 43 passes through one of the apertures 45 in the end of the arm 40 of the bell crank and is secured in position by a cotter pin or other suitable means. The stud 44 on block 42 passes through an aperture formed in the block 41, and the stud 44 is secured in proper relative position by a cotter pin or other suitable means. By providing a number of apertures 45 in the arm 40 of the bell crank, a wider adjustment in the sensitiveness of the control mechanism and the time period of the dogging action, is obtained, as the sensitiveness in the control, and the effective dogging action of the actuating pawls 12-13 on the yoke 11 may be increased or diminished by movement of the stud 43 either farther from or nearer to the point of pivotal support of the bell crank upon the post 24. The end of the link 17 is adjustably fixed in the block 42 by a clamping wing nut 46; the adjustability of the link facilitates the initial setting of the pawls in the yoke 11, and also

facilitates the adjustability of the automatic screen control mechanism to varying machines under varying conditions of use. The other end of the link 17 is connected to the ¹⁵ pawl carrying yoke 11 so that when the wire screen is traveling its normal path, the yoke 11 together with its pawls, 12—13 will be vertically reciprocated without engaging the teeth on either side of the wheel 7. When ²⁰ the wire screen departs from its normal path the pan 35 will be shifted in one direction or the other, which will in turn transmit such movement to the link 17 through the intermediate control mechanism so that the yoke ²⁵ 11 will be laterally shifted to the right or left so that one of the pawls will engage the teeth on the corresponding side to obtain a dogging or pawl and ratchet effect which will continue upon the vertical reciprocatory movement of the yoke 11, until the toothed ratchet wheel 7 has been shifted a sufficient ³⁰ distance upon the screw rod 8 to compensate for the deviation of the wire screen from its normal path, and until the wheel 7 has been brought to a position wherein upon the reciprocation of the yoke 11 the pawl carried thereby is no longer in contact with the ratchet teeth. If the movement of the wire screen is to the right (looking in the direction of the arrow, in Fig. 1) the movable end of the roller 1 is shifted to the right (looking at the end of roller, in Fig. 1) to restore the wire screen to normal and vice versa.

In order to provide for a feature of initial ³⁵ adjustability in accommodating the mechanism to a screen of given width, and in bringing the pan arm to a proper position to exert a suitable pressure, one end of the link 37 is made adjustable relative to the universal joint connection in the arm 39 of the bell crank.

The link 37 is retained in one of the blocks ⁴⁰ 47 of the universal joint connection by a clamping screw 48 in much the same manner as is the link 17 retained in the block 42 as above described.

The connection between the other end of link 37 and the lower end of the link 29 should be of such a type as will permit free rotation of the link 29 in a vertical plane, and a free and unimpaired movement of the link 37 in a substantially horizontal plane.

As shown in Figs. 2 and 6, the universal joint connection comprises a block 48 having in one end a slot in a vertical plane adapted to receive a tongue on the lower end of the link 29 said parts being pivotally connected by a pin 49; the other end of said block 48 is provided with a slotted portion in a substantially horizontal plane and is adapted to receive a tongue portion 50 which is pivotally connected with the block 48 by a pin or other suitable manner.

The present invention provides an automatic wire screen control mechanism which is

of simple and rugged construction and provides for a wide range of adjustment to varying conditions of use and to different types of machines. One desirable feature, is the simple yet rugged construction of the universal joints, which permit a free, sensitive yet positive action of the parts, and eliminates any possible lost motion, which lost motion would be fatal to accurate and sensitive control. ⁷⁰

Fig. 10 is a diagrammatic view which has been produced merely to show the general principle employed in shifting one end only of the guiding roller for the screen in order to correct and compensate for the departure of the wire screen from its normal path of travel. ⁸⁰

Fig. 8 is a diagrammatic view showing the link 17 shifted to a position so that the pawl ⁸⁵ 12 in its vertical reciprocation is in operative relation with the teeth 9. The tilting action of the yoke is exaggerated over the position actually assumed in operation.

Fig. 9 is an enlarged view showing the pan arm 31 and the guiding pan 35 in section. The guiding pan 35 is formed integral with the arm 31 so as to eliminate the necessity for any rivets or connecting means, which in the prior art frequently came in contact with the traveling wire screen and injured the same. ⁹⁰

Various modifications in the construction and operation of my device may obviously be resorted to if within the spirit and scope of my invention without departing from the limits of the appended claims. ⁹⁵

What I therefore claim and desire to secure by Letters Patent is:

1. An automatic control mechanism for wire mesh screens on a paper making machine including a guide roller movable at one end and a wire mesh screen guided thereover, a roller positioning mechanism for shifting one end of the guiding roll to control the path or course of the wire mesh screen passing thereover; an automatic control mechanism for actuating the roll positioning mechanism in accordance with variations in the travel of the wire screen mesh from its normal course, said control mechanism including a bracket, an arm pivotally supported between its ends on said bracket, another weight balanced pan arm pivotally supported between its ends upon one end of said first named arm, the upper end of the pan arm being in contact with the edge of the traveling screen and the lower end of the pan arm being weighted, the point of pivotal support of said pan arm being intermediate its ends and between the upper pan portion of the arm and the weighted portion. ¹⁰⁵

2. An automatic control mechanism for wire mesh screens on a paper making machine including a guide roller movable at one end and a wire mesh screen guided thereover, a roller positioning mechanism for shifting one ¹¹⁰ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵ ²³⁰ ²³⁵ ²⁴⁰ ²⁴⁵ ²⁵⁰ ²⁵⁵ ²⁶⁰ ²⁶⁵ ²⁷⁰ ²⁷⁵ ²⁸⁰ ²⁸⁵ ²⁹⁰ ²⁹⁵ ³⁰⁰ ³⁰⁵ ³¹⁰ ³¹⁵ ³²⁰ ³²⁵ ³³⁰ ³³⁵ ³⁴⁰ ³⁴⁵ ³⁵⁰ ³⁵⁵ ³⁶⁰ ³⁶⁵ ³⁷⁰ ³⁷⁵ ³⁸⁰ ³⁸⁵ ³⁹⁰ ³⁹⁵ ⁴⁰⁰ ⁴⁰⁵ ⁴¹⁰ ⁴¹⁵ ⁴²⁰ ⁴²⁵ ⁴³⁰ ⁴³⁵ ⁴⁴⁰ ⁴⁴⁵ ⁴⁵⁰ ⁴⁵⁵ ⁴⁶⁰ ⁴⁶⁵ ⁴⁷⁰ ⁴⁷⁵ ⁴⁸⁰ ⁴⁸⁵ ⁴⁹⁰ ⁴⁹⁵ ⁵⁰⁰ ⁵⁰⁵ ⁵¹⁰ ⁵¹⁵ ⁵²⁰ ⁵²⁵ ⁵³⁰ ⁵³⁵ ⁵⁴⁰ ⁵⁴⁵ ⁵⁵⁰ ⁵⁵⁵ ⁵⁶⁰ ⁵⁶⁵ ⁵⁷⁰ ⁵⁷⁵ ⁵⁸⁰ ⁵⁸⁵ ⁵⁹⁰ ⁵⁹⁵ ⁶⁰⁰ ⁶⁰⁵ ⁶¹⁰ ⁶¹⁵ ⁶²⁰ ⁶²⁵ ⁶³⁰ ⁶³⁵ ⁶⁴⁰ ⁶⁴⁵ ⁶⁵⁰ ⁶⁵⁵ ⁶⁶⁰ ⁶⁶⁵ ⁶⁷⁰ ⁶⁷⁵ ⁶⁸⁰ ⁶⁸⁵ ⁶⁹⁰ ⁶⁹⁵ ⁷⁰⁰ ⁷⁰⁵ ⁷¹⁰ ⁷¹⁵ ⁷²⁰ ⁷²⁵ ⁷³⁰ ⁷³⁵ ⁷⁴⁰ ⁷⁴⁵ ⁷⁵⁰ ⁷⁵⁵ ⁷⁶⁰ ⁷⁶⁵ ⁷⁷⁰ ⁷⁷⁵ ⁷⁸⁰ ⁷⁸⁵ ⁷⁹⁰ ⁷⁹⁵ ⁸⁰⁰ ⁸⁰⁵ ⁸¹⁰ ⁸¹⁵ ⁸²⁰ ⁸²⁵ ⁸³⁰ ⁸³⁵ ⁸⁴⁰ ⁸⁴⁵ ⁸⁵⁰ ⁸⁵⁵ ⁸⁶⁰ ⁸⁶⁵ ⁸⁷⁰ ⁸⁷⁵ ⁸⁸⁰ ⁸⁸⁵ ⁸⁹⁰ ⁸⁹⁵ ⁹⁰⁰ ⁹⁰⁵ ⁹¹⁰ ⁹¹⁵ ⁹²⁰ ⁹²⁵ ⁹³⁰ ⁹³⁵ ⁹⁴⁰ ⁹⁴⁵ ⁹⁵⁰ ⁹⁵⁵ ⁹⁶⁰ ⁹⁶⁵ ⁹⁷⁰ ⁹⁷⁵ ⁹⁸⁰ ⁹⁸⁵ ⁹⁹⁰ ⁹⁹⁵ ¹⁰⁰⁰ ¹⁰⁰⁵ ¹⁰¹⁰ ¹⁰¹⁵ ¹⁰²⁰ ¹⁰²⁵ ¹⁰³⁰ ¹⁰³⁵ ¹⁰⁴⁰ ¹⁰⁴⁵ ¹⁰⁵⁰ ¹⁰⁵⁵ ¹⁰⁶⁰ ¹⁰⁶⁵ ¹⁰⁷⁰ ¹⁰⁷⁵ ¹⁰⁸⁰ ¹⁰⁸⁵ ¹⁰⁹⁰ ¹⁰⁹⁵ ¹¹⁰⁰ ¹¹⁰⁵ ¹¹¹⁰ ¹¹¹⁵ ¹¹²⁰ ¹¹²⁵ ¹¹³⁰ ¹¹³⁵ ¹¹⁴⁰ ¹¹⁴⁵ ¹¹⁵⁰ ¹¹⁵⁵ ¹¹⁶⁰ ¹¹⁶⁵ ¹¹⁷⁰ ¹¹⁷⁵ ¹¹⁸⁰ ¹¹⁸⁵ ¹¹⁹⁰ ¹¹⁹⁵ ¹²⁰⁰ ¹²⁰⁵ ¹²¹⁰ ¹²¹⁵ ¹²²⁰ ¹²²⁵ ¹²³⁰ ¹²³⁵ ¹²⁴⁰ ¹²⁴⁵ ¹²⁵⁰ ¹²⁵⁵ ¹²⁶⁰ ¹²⁶⁵ ¹²⁷⁰ ¹²⁷⁵ ¹²⁸⁰ ¹²⁸⁵ ¹²⁹⁰ ¹²⁹⁵ ¹³⁰⁰ ¹³⁰⁵ ¹³¹⁰ ¹³¹⁵ ¹³²⁰ ¹³²⁵ ¹³³⁰ ¹³³⁵ ¹³⁴⁰ ¹³⁴⁵ ¹³⁵⁰ ¹³⁵⁵ ¹³⁶⁰ ¹³⁶⁵ ¹³⁷⁰ ¹³⁷⁵ ¹³⁸⁰ ¹³⁸⁵ ¹³⁹⁰ ¹³⁹⁵ ¹⁴⁰⁰ ¹⁴⁰⁵ ¹⁴¹⁰ ¹⁴¹⁵ ¹⁴²⁰ ¹⁴²⁵ ¹⁴³⁰ ¹⁴³⁵ ¹⁴⁴⁰ ¹⁴⁴⁵ ¹⁴⁵⁰ ¹⁴⁵⁵ ¹⁴⁶⁰ ¹⁴⁶⁵ ¹⁴⁷⁰ ¹⁴⁷⁵ ¹⁴⁸⁰ ¹⁴⁸⁵ ¹⁴⁹⁰ ¹⁴⁹⁵ ¹⁵⁰⁰ ¹⁵⁰⁵ ¹⁵¹⁰ ¹⁵¹⁵ ¹⁵²⁰ ¹⁵²⁵ ¹⁵³⁰ ¹⁵³⁵ ¹⁵⁴⁰ ¹⁵⁴⁵ ¹⁵⁵⁰ ¹⁵⁵⁵ ¹⁵⁶⁰ ¹⁵⁶⁵ ¹⁵⁷⁰ ¹⁵⁷⁵ ¹⁵⁸⁰ ¹⁵⁸⁵ ¹⁵⁹⁰ ¹⁵⁹⁵ ¹⁶⁰⁰ ¹⁶⁰⁵ ¹⁶¹⁰ ¹⁶¹⁵ ¹⁶²⁰ ¹⁶²⁵ ¹⁶³⁰ ¹⁶³⁵ ¹⁶⁴⁰ ¹⁶⁴⁵ ¹⁶⁵⁰ ¹⁶⁵⁵ ¹⁶⁶⁰ ¹⁶⁶⁵ ¹⁶⁷⁰ ¹⁶⁷⁵ ¹⁶⁸⁰ ¹⁶⁸⁵ ¹⁶⁹⁰ ¹⁶⁹⁵ ¹⁷⁰⁰ ¹⁷⁰⁵ ¹⁷¹⁰ ¹⁷¹⁵ ¹⁷²⁰ ¹⁷²⁵ ¹⁷³⁰ ¹⁷³⁵ ¹⁷⁴⁰ ¹⁷⁴⁵ ¹⁷⁵⁰ ¹⁷⁵⁵ ¹⁷⁶⁰ ¹⁷⁶⁵ ¹⁷⁷⁰ ¹⁷⁷⁵ ¹⁷⁸⁰ ¹⁷⁸⁵ ¹⁷⁹⁰ ¹⁷⁹⁵ ¹⁸⁰⁰ ¹⁸⁰⁵ ¹⁸¹⁰ ¹⁸¹⁵ ¹⁸²⁰ ¹⁸²⁵ ¹⁸³⁰ ¹⁸³⁵ ¹⁸⁴⁰ ¹⁸⁴⁵ ¹⁸⁵⁰ ¹⁸⁵⁵ ¹⁸⁶⁰ ¹⁸⁶⁵ ¹⁸⁷⁰ ¹⁸⁷⁵ ¹⁸⁸⁰ ¹⁸⁸⁵ ¹⁸⁹⁰ ¹⁸⁹⁵ ¹⁹⁰⁰ ¹⁹⁰⁵ ¹⁹¹⁰ ¹⁹¹⁵ ¹⁹²⁰ ¹⁹²⁵ ¹⁹³⁰ ¹⁹³⁵ ¹⁹⁴⁰ ¹⁹⁴⁵ ¹⁹⁵⁰ ¹⁹⁵⁵ ¹⁹⁶⁰ ¹⁹⁶⁵ ¹⁹⁷⁰ ¹⁹⁷⁵ ¹⁹⁸⁰ ¹⁹⁸⁵ ¹⁹⁹⁰ ¹⁹⁹⁵ ²⁰⁰⁰ ²⁰⁰⁵ ²⁰¹⁰ ²⁰¹⁵ ²⁰²⁰ ²⁰²⁵ ²⁰³⁰ ²⁰³⁵ ²⁰⁴⁰ ²⁰⁴⁵ ²⁰⁵⁰ ²⁰⁵⁵ ²⁰⁶⁰ ²⁰⁶⁵ ²⁰⁷⁰ ²⁰⁷⁵ ²⁰⁸⁰ ²⁰⁸⁵ ²⁰⁹⁰ ²⁰⁹⁵ ²¹⁰⁰ ²¹⁰⁵ ²¹¹⁰ ²¹¹⁵ ²¹²⁰ ²¹²⁵ ²¹³⁰ ²¹³⁵ ²¹⁴⁰ ²¹⁴⁵ ²¹⁵⁰ ²¹⁵⁵ ²¹⁶⁰ ²¹⁶⁵ ²¹⁷⁰ ²¹⁷⁵ ²¹⁸⁰ ²¹⁸⁵ ²¹⁹⁰ ²¹⁹⁵ ²²⁰⁰ ²²⁰⁵ ²²¹⁰ ²²¹⁵ ²²²⁰ ²²²⁵ ²²³⁰ ²²³⁵ ²²⁴⁰ ²²⁴⁵ ²²⁵⁰ ²²⁵⁵ ²²⁶⁰ ²²⁶⁵ ²²⁷⁰ ²²⁷⁵ ²²⁸⁰ ²²⁸⁵ ²²⁹⁰ ²²⁹⁵ ²³⁰⁰ ²³⁰⁵ ²³¹⁰ ²³¹⁵ ²³²⁰ ²³²⁵ ²³³⁰ ²³³⁵ ²³⁴⁰ ²³⁴⁵ ²³⁵⁰ ²³⁵⁵ ²³⁶⁰ ²³⁶⁵ ²³⁷⁰ ²³⁷⁵ ²³⁸⁰ ²³⁸⁵ ²³⁹⁰ ²³⁹⁵ ²⁴⁰⁰ ²⁴⁰⁵ ²⁴¹⁰ ²⁴¹⁵ ²⁴²⁰ ²⁴²⁵ ²⁴³⁰ ²⁴³⁵ ²⁴⁴⁰ ²⁴⁴⁵ ²⁴⁵⁰ ²⁴⁵⁵ ²⁴⁶⁰ ²⁴⁶⁵ ²⁴⁷⁰ ²⁴⁷⁵ ²⁴⁸⁰ ²⁴⁸⁵ ²⁴⁹⁰ ²⁴⁹⁵ ²⁵⁰⁰ ²⁵⁰⁵ ²⁵¹⁰ ²⁵¹⁵ ²⁵²⁰ ²⁵²⁵ ²⁵³⁰ ²⁵³⁵ ²⁵⁴⁰ ²⁵⁴⁵ ²⁵⁵⁰ ²⁵⁵⁵ ²⁵⁶⁰ ²⁵⁶⁵ ²⁵⁷⁰ ²⁵⁷⁵ ²⁵⁸⁰ ²⁵⁸⁵ ²⁵⁹⁰ ²⁵⁹⁵ ²⁶⁰⁰ ²⁶⁰⁵ ²⁶¹⁰ ²⁶¹⁵ ²⁶²⁰ ²⁶²⁵ ²⁶³⁰ ²⁶³⁵ ²⁶⁴⁰ ²⁶⁴⁵ ²⁶⁵⁰ ²⁶⁵⁵ ²⁶⁶⁰ ²⁶⁶⁵ ²⁶⁷⁰ ²⁶⁷⁵ ²⁶⁸⁰ ²⁶⁸⁵ ²⁶⁹⁰ ²⁶⁹⁵ ²⁷⁰⁰ ²⁷⁰⁵ ²⁷¹⁰ ²⁷¹⁵ ²⁷²⁰ ²⁷²⁵ ²⁷³⁰ ²⁷³⁵ ²⁷⁴⁰ ²⁷⁴⁵ ²⁷⁵⁰ ²⁷⁵⁵ ²⁷⁶⁰ ²⁷⁶⁵ ²⁷⁷⁰ ²⁷⁷⁵ ²⁷⁸⁰ ²⁷⁸⁵ ²⁷⁹⁰ ²⁷⁹⁵ ²⁸⁰⁰ ²⁸⁰⁵ ²⁸¹⁰ ²⁸¹⁵ ²⁸²⁰ ²⁸²⁵ ²⁸³⁰ ²⁸³⁵ ²⁸⁴⁰ ²⁸⁴⁵ ²⁸⁵⁰ ²⁸⁵⁵ ²⁸⁶⁰ ²⁸⁶⁵ ²⁸⁷⁰ ²⁸⁷⁵ ²⁸⁸⁰ ²⁸⁸⁵ ²⁸⁹⁰ ²⁸⁹⁵ ²⁹⁰⁰ ²⁹⁰⁵ ²⁹¹⁰ ²⁹¹⁵ ²⁹²⁰ ²⁹²⁵ ²⁹³⁰ ²⁹³⁵ ²⁹⁴⁰ ²⁹⁴⁵ ²⁹⁵⁰ ²⁹⁵⁵ ²⁹⁶⁰ ²⁹⁶⁵ ²⁹⁷⁰ ²⁹⁷⁵ ²⁹⁸⁰ ²⁹⁸⁵ ²⁹⁹⁰ ²⁹⁹⁵ ³⁰⁰⁰ ³⁰⁰⁵ ³⁰¹⁰ ³⁰¹⁵ ³⁰²⁰ ³⁰²⁵ ³⁰³⁰ ³⁰³⁵ ³⁰⁴⁰ ³⁰⁴⁵ ³⁰⁵⁰ ³⁰⁵⁵ ³⁰⁶⁰ ³⁰⁶⁵ ³⁰⁷⁰ ³⁰⁷⁵ ³⁰⁸⁰ ³⁰⁸⁵ ³⁰⁹⁰ ³⁰⁹⁵ ³¹⁰⁰ ³¹⁰⁵ ³¹¹⁰ ³¹¹⁵ ³¹²⁰ ³¹²⁵ ³¹³⁰ ³¹³⁵ ³¹⁴⁰ ³¹⁴⁵ ³¹⁵⁰ ³¹⁵⁵ ³¹⁶⁰ ³¹⁶⁵ ³¹⁷⁰ ³¹⁷⁵ ³¹⁸⁰ ³¹⁸⁵ ³¹⁹⁰ ³¹⁹⁵ ³²⁰⁰ ³²⁰⁵ ³²¹⁰ ³²¹⁵ ³²²⁰ ³²²⁵ ³²³⁰ ³²³⁵ ³²⁴⁰ ³²⁴⁵ ³²⁵⁰ ³²⁵⁵ ³²⁶⁰ ³²⁶⁵ ³²⁷⁰ ³²⁷⁵ ³²⁸⁰ ³²⁸⁵ ³²⁹⁰ ³²⁹⁵ ³³⁰⁰ ³³⁰⁵ ³³¹⁰ ³³¹⁵ ³³²⁰ ³³²⁵ ³³³⁰ ³³³⁵ ³³⁴⁰ ³³⁴⁵ ³³⁵⁰ ³³⁵⁵ ³³⁶⁰ ³³⁶⁵ ³³⁷⁰ ³³⁷⁵ ³³⁸⁰ ³³⁸⁵ ³³⁹⁰ ³³⁹⁵ ³⁴⁰⁰ ³⁴⁰⁵ ³⁴¹⁰ ³⁴¹⁵ ³⁴²⁰ ³⁴²⁵ ³⁴³⁰ ³⁴³⁵ ³⁴⁴⁰ ³⁴⁴⁵ ³⁴⁵⁰ ³⁴⁵⁵ ³⁴⁶⁰ ³⁴⁶⁵ ³⁴⁷⁰ ³⁴⁷⁵ ³⁴⁸⁰ ³⁴⁸⁵ ³⁴⁹⁰ ³⁴⁹⁵ ³⁵⁰⁰ ³⁵⁰⁵ ³⁵¹⁰ ³⁵¹⁵ ³⁵²⁰ ³⁵²⁵ ³⁵³⁰ ³⁵³⁵ ³⁵⁴⁰ ³⁵⁴⁵ ³⁵⁵⁰ ³⁵⁵⁵ ³⁵⁶⁰ ³⁵⁶⁵ ³⁵⁷⁰ ³⁵⁷⁵ ³⁵⁸⁰ ³⁵⁸⁵ ³⁵⁹⁰ ³⁵⁹⁵ ³⁶⁰⁰ ³⁶⁰⁵ ³⁶¹⁰ ³⁶¹⁵ ³⁶²⁰ ³⁶²⁵ ³⁶³⁰ ³⁶³⁵ ³⁶⁴⁰ ³⁶⁴⁵ ³⁶⁵⁰ ³⁶⁵⁵ ³⁶⁶⁰ ³⁶⁶⁵ ³⁶⁷⁰ ³⁶⁷⁵ ³⁶⁸⁰ ³⁶⁸⁵ ³⁶⁹⁰ ³⁶⁹⁵ ³⁷⁰⁰ ³⁷⁰⁵ ³⁷¹⁰ ³⁷¹⁵ ³⁷²⁰ ³⁷²⁵ ³⁷³⁰ ³⁷³⁵ ³⁷⁴⁰ ³⁷⁴⁵ ³⁷⁵⁰ ³⁷⁵⁵ ³⁷⁶⁰ ³⁷⁶⁵ ³⁷⁷⁰ ³⁷⁷⁵ ³⁷⁸⁰ ³⁷⁸⁵ ³⁷⁹⁰ ³⁷⁹⁵ ³⁸⁰⁰ ³⁸⁰⁵ ³⁸¹⁰ ³⁸¹⁵ ³⁸²⁰ ³⁸²⁵ ³⁸³⁰ ³⁸³⁵ ³⁸⁴⁰ ³⁸⁴⁵ ³⁸⁵⁰ ³⁸⁵⁵ ³⁸⁶⁰ ³⁸⁶⁵ ³⁸⁷⁰ ³⁸⁷⁵ ³⁸⁸⁰ ³⁸⁸⁵ ³⁸⁹⁰ ³⁸⁹⁵ ³⁹⁰⁰ ³⁹⁰⁵ ³⁹¹⁰ ³⁹¹⁵ ³⁹²⁰ ³⁹²⁵ ³⁹³⁰ ³⁹³⁵ ³⁹⁴⁰ ³⁹⁴⁵ ³⁹⁵⁰ ³⁹⁵⁵ ³⁹⁶⁰ ³⁹⁶⁵ ³⁹⁷⁰ ³⁹⁷⁵ ³⁹⁸⁰ ³⁹⁸⁵ ³⁹⁹⁰ ³⁹⁹⁵ ⁴⁰⁰⁰ ⁴⁰⁰⁵ ⁴⁰¹⁰ ⁴⁰¹⁵ ⁴⁰²⁰ ⁴⁰²⁵ ⁴⁰³⁰ ⁴⁰³⁵ ⁴⁰⁴⁰ ⁴⁰⁴⁵ ⁴⁰⁵⁰ ⁴⁰⁵⁵ ⁴⁰⁶⁰ ⁴⁰⁶⁵ ⁴⁰⁷⁰ ⁴⁰⁷⁵ ⁴⁰⁸⁰ ⁴⁰⁸⁵ ⁴⁰⁹⁰ ⁴⁰⁹⁵ ⁴¹⁰⁰ ⁴¹⁰⁵ ⁴¹¹⁰ ⁴¹¹⁵ ⁴¹²⁰ ⁴¹²⁵ ⁴¹³⁰ ⁴¹³⁵ ⁴¹⁴⁰ ⁴¹⁴⁵ ⁴¹⁵⁰ ⁴¹⁵⁵ ⁴¹⁶⁰ ⁴¹⁶⁵ ⁴¹⁷⁰ ⁴¹⁷⁵ ⁴¹⁸⁰ ⁴¹⁸⁵ ⁴¹⁹⁰ ⁴¹⁹⁵ ⁴²⁰⁰ ⁴²⁰⁵ ⁴²¹⁰ ⁴²¹⁵ ⁴²²⁰ ⁴²²⁵ ⁴²³⁰ ⁴²³⁵ ⁴²⁴⁰ ⁴²⁴⁵ ⁴²⁵⁰ ⁴²⁵⁵ ⁴²⁶⁰ ⁴²⁶⁵ ⁴²⁷⁰ ⁴²⁷⁵ ⁴²⁸⁰ ⁴²⁸⁵ ⁴²⁹⁰ ⁴²⁹⁵ ⁴³⁰⁰ ⁴³⁰⁵ ⁴³¹⁰ ⁴³¹⁵ ⁴³²⁰ ⁴³²⁵ ⁴³³⁰ ⁴³³⁵ ⁴³⁴⁰ ⁴³⁴⁵ ⁴³⁵⁰ ⁴³⁵⁵ ⁴³⁶⁰ ⁴³⁶⁵ ⁴³⁷⁰ ⁴³⁷⁵ ⁴³⁸⁰ ⁴³⁸⁵ ⁴³⁹⁰ ⁴³⁹⁵ ⁴⁴⁰⁰ ⁴⁴⁰⁵ ⁴⁴¹⁰ ⁴⁴¹⁵ ⁴⁴²⁰ ⁴⁴²⁵ ⁴⁴³⁰ ⁴⁴³⁵ ⁴⁴⁴⁰ ⁴⁴⁴⁵ ⁴⁴⁵⁰ ⁴⁴⁵⁵ ⁴⁴⁶⁰ ⁴⁴⁶⁵ ⁴⁴⁷⁰ ⁴⁴⁷⁵ ⁴⁴⁸⁰ ⁴⁴⁸⁵ ⁴⁴⁹⁰ ⁴⁴⁹⁵ ⁴⁵⁰⁰ ⁴⁵⁰⁵ ⁴⁵¹⁰ ⁴⁵¹⁵ ⁴⁵²⁰ ⁴⁵²⁵ ⁴⁵³⁰ ⁴⁵³⁵ ⁴⁵⁴⁰ ⁴⁵⁴⁵ ⁴⁵⁵⁰ ⁴⁵⁵⁵ ⁴⁵⁶⁰ ⁴⁵⁶⁵ ⁴⁵⁷⁰ ⁴⁵⁷⁵ ⁴⁵⁸⁰ ⁴⁵⁸⁵ ⁴⁵⁹⁰ ⁴⁵⁹⁵ ⁴⁶⁰⁰ ⁴⁶⁰⁵ ⁴⁶¹⁰ ⁴⁶¹⁵ ⁴⁶²⁰ ⁴⁶²⁵ ⁴⁶³⁰ ⁴⁶³⁵ ⁴⁶⁴⁰ ⁴⁶⁴⁵ ⁴⁶⁵⁰ ⁴⁶⁵⁵ ⁴⁶⁶⁰ ⁴⁶⁶⁵ ⁴⁶⁷⁰ ⁴⁶⁷⁵ ⁴⁶⁸⁰ ⁴⁶⁸⁵ ⁴⁶⁹⁰ ⁴⁶⁹⁵ ⁴⁷⁰⁰ ⁴⁷⁰⁵ ⁴⁷¹⁰ ⁴⁷¹⁵ ⁴⁷²⁰ ⁴⁷²⁵ ⁴⁷³⁰ ⁴⁷³⁵ ⁴⁷⁴⁰ ⁴⁷⁴⁵ ⁴⁷⁵⁰ ⁴⁷⁵⁵ ⁴⁷⁶⁰ ⁴⁷⁶⁵ ⁴⁷⁷⁰ ⁴⁷⁷⁵ ⁴⁷⁸⁰ ⁴⁷⁸⁵ ⁴⁷⁹⁰ ⁴⁷⁹⁵ ⁴⁸⁰⁰ ⁴⁸⁰⁵ ⁴⁸¹⁰ ⁴⁸¹⁵ ⁴⁸²⁰ ⁴⁸²⁵ ⁴⁸³⁰ ⁴⁸³⁵ ⁴⁸⁴⁰ ⁴⁸⁴⁵ ⁴⁸⁵⁰ ⁴⁸⁵⁵ ⁴⁸⁶⁰ ⁴⁸⁶⁵ ⁴⁸⁷⁰ ⁴⁸⁷⁵ ⁴⁸⁸⁰ ⁴⁸⁸⁵ ⁴⁸⁹⁰ ⁴⁸⁹⁵ ⁴⁹⁰⁰ ⁴⁹⁰⁵ ⁴⁹¹⁰ ⁴⁹¹⁵ ⁴⁹²⁰ ⁴⁹²⁵ ⁴⁹³⁰ ⁴⁹³⁵ ⁴⁹⁴⁰ ⁴⁹⁴⁵ ⁴⁹⁵⁰ ⁴⁹⁵⁵ ⁴⁹⁶⁰ ⁴⁹⁶⁵ ⁴⁹⁷⁰ ⁴⁹⁷⁵ ⁴⁹⁸⁰ ⁴⁹⁸⁵ ⁴⁹⁹⁰ ⁴⁹⁹⁵ ⁵⁰⁰⁰

- end of the guiding roll to control the path or course of the wire mesh screen passing thereover, an automatic control mechanism for actuating the roll positioning mechanism in accordance with variations in the travel of the wire screen mesh from its normal course, said control mechanism including a bracket 5 and an upstanding arm adjustable on said bracket, a second arm pivotally supported intermediate its ends on said upstanding arm, a weight controlled guiding pan pivotally mounted on said second arm and adapted to be actuated by the wire mesh screen upon deviation from its normal path of travel and mechanism actuated by the movement of said guiding pan and interposed between said pan and said roll positioning mechanism, whereby the force effective upon the roll positioning mechanism is indirectly transmitted 10 through an intermediate pivoted weight controlled arm.
3. An automatic control mechanism for wire mesh screens on a paper making machine including a guide roller movable at one end and a wire mesh screen guided thereover, a roller positioning mechanism for shifting one end of the guiding roll to control the path or course of the wire mesh screen passing thereover, an automatic control mechanism 15 for actuating the roll positioning mechanism in accordance with variations in the travel of the wire screen mesh from its normal course, said control mechanism including means permitting the use of said control mechanism on either a right hand or left hand machine, said means including a bracket and bell crank 20 removably pivoted on said bracket, an arm pivotally mounted between its ends on said bracket, a weight balanced pan arm pivotally mounted on said first arm the point of pivotal support being between the pan portion contacting with the screen and the weighted portion of the arm, a link connecting said positioning mechanism and one arm of said bell crank and a link connecting the other arm of the bell crank with the said arm which is 25 pivotally mounted between its ends on said bracket.
6. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism 30 for actuating the roll positioning mechanism in accordance with variations in the travel of the wire screen mesh from its normal course, said control mechanism including a bracket, an arm pivotally supported between its ends on the upper end of said upstanding arm, a weight controlled guiding pan arm pivotally mounted on said second named arm which is pivotally supported between its ends and adapted to be actuated by the wire mesh screen upon deviation from its normal path of travel the pivotal connection of said pan arm being between the weighted end and the pan portion contacting with the screen and mechanism actuated by the movement of said guiding pan and interposed between said pan and said 35 roll positioning mechanism.
4. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism for actuating the roll positioning mechanism in accordance with variations in the travel of the wire screen mesh from its normal course, said control mechanism including means permitting the use of said control mechanism on either a right hand or left hand machine, said means including a bracket and bell crank re- 40 movably pivoted on said bracket, a link connecting said positioning mechanism and one arm of said bell crank and a universal joint connection between one end of said link and said arm.
5. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism for actuating the roll positioning mechanism in accordance with variations in the travel of the wire screen mesh from its normal course, said control mechanism including means permitting the use of said control mechanism on either a right hand or left hand machine, said means including a bracket and bell crank 45 removably pivoted on said bracket, an arm pivotally mounted between its ends on said bracket, a weight balanced pan arm pivotally mounted on said first arm the point of pivotal support being between the pan portion contacting with the screen and the weighted portion of the arm, a link connecting said positioning mechanism and one arm of said bell crank and a link connecting the other arm of the bell crank with the said arm which is pivotally mounted between its ends on said bracket.
6. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism 50 for actuating the roll positioning mechanism in accordance with variations in the travel of the wire screen mesh from its normal course, said control mechanism including a bracket, an arm pivotally supported between its ends on said bracket, a weight balanced pan arm pivotally mounted on said first arm, the point of pivotal support being between the pan portion of the arm contacting with the screen and the weighted end of the pan arm and bell crank removably pivoted on said bracket, a link connecting one arm of the bell crank and said first named pivotally supported arm, a link connecting said positioning mechanism and the other arm of said bell crank and a universal joint connection between one end of said link and said arm, and a means for adjustably securing one end of said link in the universal joint.
7. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism for actuating the roll positioning mechanism in accordance with variations in the travel of the wire screen mesh from its normal course, said control mechanism including means permitting the use of said control mechanism on either a right hand or left hand machine, said means including a bracket and bell crank re- 55 movably pivoted on said bracket, a link connecting said positioning mechanism and one arm of said bell crank and a universal joint connection between one end of said link and said arm.

course of the wire mesh screen passing thereover, an automatic control mechanism for actuating the roll positioning mechanism in accordance with variations in the travel of the wire screen mesh from its normal course, 5 said control mechanism including means permitting the use of said control mechanism on either a right hand or left hand machine, said means including a bracket and bell crank removably pivoted on said bracket, a link connecting said positioning mechanism and one arm of said bell crank and a universal joint connection between one end of said link and said arm, and a means to adjust the sensitiveness of the control by varying the time period during which the automatic control mechanism is effective for any given departure of the wire screen from its normal path of movement.

20 8. An automatic control mechanism for wire mesh screens on paper making machines including a guide roller movable at one end and a wire mesh screen guided thereover, a roller positioning mechanism for shifting 25 one end of the guiding roll to control the path or course of the wire mesh screen passing thereover, an automatic control mechanism for actuating the roll positioning mechanism in accordance with variations in the travel of the wire screen mesh from its normal course, said control mechanism including means permitting the use of said control mechanism on either a right hand or left hand machine, said means including a bracket and bell crank removably pivoted on said bracket, a link connecting said positioning mechanism and one arm of said bell crank, a universal joint connection between one end of said link and said arm, and means for varying the throw of said link for any given departure of movement of said wire screen from its normal path whereby the sensitiveness of control may be regulated.

9. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism for actuating the roll positioning mechanism in accordance with variations in the travel of the wire screen mesh from its normal course, 55 said control mechanism including means permitting the use of said control mechanism on either a right hand or left hand machine, said means including a bracket and bell crank removably pivoted on said bracket, a link connecting said positioning mechanism and one arm of said bell crank, a universal joint connection between one end of said link and said arm, and means for varying the throw of said link for any given departure of movement of said wire screen from its normal path

whereby the sensitiveness of control may be regulated, said means including a plurality of apertures in one arm of the bell crank, permitting the mounting of the stud of the universal joint at varying distances from the point of pivotal support of said arm.

10. An automatic control mechanism for wire mesh screens on paper making machines including a guide roller movable at one end and a wire mesh screen guided thereover, a roller positioning mechanism for shifting one end of the guiding roll to control the path or course of the wire mesh screen passing thereover, an automatic control mechanism for actuating the roll positioning mechanism in accordance with variations in the travel of the wire screen mesh from its normal course, said control mechanism including a weight balanced pan arm adapted to engage the traveling edge of the screen, a bracket, an arm pivotally supported between its ends on the bracket, a pivotal support on said last named arm for said weight balanced pan, said point of pivotal support being between the point at which the pan contacts with the wire screen and the weight, whereby upon abnormal shifting of the screen to one side a yielding pressure is exerted against the traveling edge of the screen by the pan arm, which pressure is determined only by the effect of the weight of the arm which has been deflected so that the edge of the screen is not injured.

In testimony whereof I affix my signature.

WILLIAM J. TREMPE.
